UNITED STATES PATENT OFFICE.

WILLIAM F. KELLETT, OF CHICAGO, ILLINOIS.

DESIGN FOR A PLASTER CENTER-PIECE.

SPECIFICATION forming part of Design No. 14,258, dated September 4, 1883.

Application filed December 1, 1882. Term of patent 14 years.

To all whom it may concern:

Be it known that I, WILLIAM F. KELLETT, a citizen of the United States, residing at Chicago, in the county of Cook and State of Illinois, have invented a new and original Design for Plaster Center-Pieces for Rooms, of which the following is a true and correct specification, reference being had to the accompanying engraving, in which—

10 The figure represents my design, which consists of a frame, A, composed of four segments of circles with rosettes in the molding thereof. In the center of my design is a ring, F, of scallop and pyramid work, as shown in the 15 engraving. Resting upon the ring F, and on two opposite sides thereof, are segments of circles E, with pointed scallops, as shown in the figure. At two other points of said circle F, said points being opposite each other, there 20 rests a base of scallop and banded Gothic leaves, C, in the center of which are scalloped and horseshoe ornaments D. Within said segments, and opposite each other and radiating from

one center, are bunches of buds and berries B, said bunches of buds and berries on two sides 25 opposite each other resting upon said segment E, and on the other two sides resting upon the horseshoe-shaped ornament D and scalloped and banded Gothic leaves C, all as shown in the said engraving.

30 I claim—

A frame, A, composed of four segments of 35 molded circles with rosettes in the molding thereof, and containing within said segments bunches of buds and berries B, with stems resting in scalloped and banded Gothic leaf C and horseshoe-shaped ornaments D, arranged 40 opposite each other on two sides, and said buds and berries on the other two sides resting in segments of circles E, with pointed scallops, all substantially as described.

WILLIAM F. KELLETT.
